UNITED STATES PATENT OFFICE

WILLIAM J. MACFARLAND, OF BOSTON, MASSACHUSETTS.

INNERSOLE FOR SHOES.

1,128,994.

Specification of Letters Patent. Patented Feb. 16, 1915.

Application filed November 18, 1913. Serial No. 801,731.

To all whom it may concern:

Be it known that I, WILLIAM J. MACFARLAND, a citizen of the United States of America, and a resident of Boston, in the county of Suffolk and State of Massachusetts, have invented certain new and useful Improvements in Innersoles for Shoes, of which the following is a specification.

This invention relates to inner soles for boots and shoes and has for its object the production of a sole particularly adapted for use in shoes in which a very flexible shank is desired.

The invention consists in a sole having a rib extending from the front of the shank on its inside around the toe to the heel on its outside and having a high arch on the inside of said shank with its under face chamfered off from the channel on the outside to a thin edge on the inner side.

The invention further consists in certain novel features of construction and arrangement of parts which will be fully understood by reference to the description of the drawings and to the claims hereinafter given.

Of the drawings: Figure 1 represents a plan of an inner sole embodying the principles of the present invention. Fig. 2 represents an inverted plan of the same. Fig. 3 represents an elevation of the same in position to be placed on a last. Fig. 4 represents a section through the fore part, the cutting plane being on line 4—4 on Fig. 2, and Fig. 5 represents a section through the shank part, the cutting plane being on line 5—5 on Fig. 2.

Similar characters designate like parts throughout the several figures of the drawings.

In the drawings, 10 is the inner sole having formed on its under face the rib 11 extending from the front of the shank 12 on the inside around the toe to the heel seat 13. Between the heel seat 13 and the end 14 of the rib 11 the shank is chamfered off from the channel 15 on the outside of the shank to nearly a feather edge on the inside thereof. The purpose of this chamfering off of the shank on the inside is to give this portion of the inner sole great flexibility so that it may be sprung up while being secured in the shoe thus forming a yielding arch which will support the arch of the foot. The blank when cut is formed as shown in Fig.

2 of the drawings with the heel part 13 in 55 the position shown in dotted lines.

After the blank has been cut and its shank chamfered off as indicated in Fig. 5, the fore part is secured to a last and then the heel part is sprung into the position shown 60 in full lines in Fig. 2 and the thinner portion of the shank is worked down into the hollow formed in the shank of the last. If the inner sole while in this position is secured to a shoe a high yielding arch will be 65 formed at the shank which is adapted to support the arch of the foot and will buckle upwardly with every forward step taken by the wearer of the shoe.

By this construction the arch is permanently supported when support is most needed, that is, during walking and running. The springing of the blank into the shape shown in the accompanying drawings may be accomplished during the construction of 75 the shoe or prior thereto as desired.

It is obvious that the rib 11 will stiffen the outside of the shank so that the flexible arched portion 16 will be on the inside of the shank and conform to the arch of the 80 foot of the person wearing the shoe, the springing of the inner sole being in accordance with certain well-defined principles of manufacturing shoes on scientific lines.

By the use of an inner sole constructed 85 as shown and described a shoe may be made without the usual metal shank support and a natural support given to the arch of the wearer's foot which will yield when necessary during the various movements of the 90 foot.

It is believed that the many advantages of this invention will be fully understood from the foregoing description.

Having thus described my invention, I 95 claim:

1. An inner sole provided with a channel in its under face along the outer edge of its shank portion and having the under face of the shank portion chamfered off from said channel to a thin inner edge, the heel portion of said sole being offset from the fore part and adapted to be moved laterally in the manufacture of the shoe, thereby forcing the chamfered off portion of the shank upwardly and forming a high yielding arch 100 on the inside of the shank.

2. An inner sole having the under face of

its shank chamfered off at the inside and its heel portion formed offset relative to the fore part thereof so that it may be moved laterally thereto in the manufacture of the
5 shoe thereby, forcing upwardly said chamfered off portion and forming a high yielding arch support on the inside of the shank.

Signed by me at 4 Post Office Sq., Boston,
Mass., this 13th day of November, 1913.

WILLIAM J. MACFARLAND.
